UNITED STATES PATENT OFFICE.

JOSEPH P. GRAHAM, OF CHESTER, KENTUCKY.

BILGE-WATER EJECTOR.

SPECIFICATION forming part of Letters Patent No. 271,060, dated January 23, 1883.

Application filed September 23, 1882. (No model.)

To all whom it may concern:

Be it known that I, JOSEPH P. GRAHAM, a citizen of the United States, and a resident of Chester, in the county of Mason and State of Kentucky, have invented a new and valuable Improvement in Ejector-Plugs; and I do hereby declare that the following is a full, clear, and exact description of the construction and operation of the same, reference being had to the annexed drawing, making a part of this specification, and to the letters and figures of reference marked thereon.

The figure of the drawing is a vertical section.

15 The object of this invention is to provide means for automatically discharging the bilge-water from boats of all classes, so as to obviate the necessity of pumping or bailing out the water.

20 To such end I provide a pipe, A, which is screwed or otherwise tightly fitted in an opening formed through the bottom of the boat. The lower and smaller end, a, of this pipe is bent and turned toward the stern of the boat, 25 while in the upper end, which is provided with a valve-seat, B, is arranged a downwardly-opening check-valve, C. The upper end of the pipe has the annular exterior flange, D, which fits against the bottom of the boat so as to 30 steady the device. When there is no water in the boat the upward pressure of the water within the pipe will raise the valve and close

it against its seat. When, however, the water in the boat rises above the valve and the boat is in motion the valve will drop and open and 35 the water be drawn off by the vacuum created in rear of the small end of the pipe.

A curved tube leading from a hole in the bottom of the vessel and opening toward the stern of the same into a horizontal pipe secured under the bottom of the vessel and extending in the direction of its length has been provided with a valve operated by a screw-rod from either of the decks or some other support prior to my invention; but this device is not wholly 45 automatic, while mine is, it being necessary in the construction just mentioned to operate the screw-rod to start and stop the device.

Having thus described my invention, what I claim is—

50 The combination, with the pipe A, flanged at its upper end and bent at its lower end, which extends toward the stern of a boat, below the bottom of the latter, of the downwardly-opening automatic check-valve arranged in 55 the upper end of the pipe, substantially as described.

In testimony that I claim the above I have hereunto subscribed my name in the presence of two witnesses.

JOSEPH PATTERSON GRAHAM.
